(57) **CLAIM**

The ornamental design for a hand tool, as shown and described.

DESCRIPTION

FIG. 1 is a perspective view of a hand tool.

FIG. 2 is a left side elevation of the hand tool. A right side elevation of the hand tool is not shown because it is a mirror image of the left side elevation.

FIG. 3 is a top plan view of the hand tool.

FIG. 4 is a bottom plan view of the hand tool.

FIG. 5 is a front elevation of the hand tool; and,
FIG. 6 is a rear elevation view of the hand tool.

The broken lines are directed to the environmental structure
defining the boundary of the claimed portions of the hand
tool handle and form no part of the claimed design.
